UNITED STATES PATENT OFFICE.

JOHN DU BOIS, OF EUTAW, ALABAMA.

COTTON-GIN.

SPECIFICATION forming part of Letters Patent No. 237,433, dated February 8, 1881.

Application filed March 20, 1880. (No model.)

To all whom it may concern:

Be it known that I, JOHN DU BOIS, a citizen of the United States, residing at Eutaw, in the county of Greene and State of Alabama, 5 have invented certain new and useful Improvements in Cotton-Gins; and I do hereby declare that the following is a full, clear, and exact description of the same, reference being had to the annexed drawings, making a part of 10 this specification, and to the letters and figures of reference marked thereon.

Figure 1 in the drawings is a side elevation of my invention, partly in section; Fig. 2, a vertical section thereof, and Figs. 3 and 4 detail views.

This invention has relation to certain novel improvements in cotton-gins, as will be hereinafter described, and subsequently pointed out in the claims.

20 In the accompanying drawings, A represents the frame of the cotton-gin, to which is journaled the brush B, having secured to its shaft a pulley, a, over which passes a belt, b, said belt passing around a pulley, c, and to 25 and around a large pulley, d, upon the shaft e of the circular saws C, by which arrangement both the brush B and saws C are caused to rotate.

Above the saws C, in a line diagonal to their 30 axes, is arranged a fan, D, having upon its shaft a pulley, f, which connects with a friction-pulley, g, by a belt, h. This friction-pulley g has its bearing in the end of a yielding plate, E, so that the roller secured to said pulley will have capacity of rising over any obstructions, such as cotton-seed, &c. This plate 35 E has an elongated slot, i, through which passes a bolt or screw, j, in contact with the frame of the machine, for the purpose of limiting the upward movement of said plate and of the roller operated by the pulley g. The periphery of the roller or pulley g comes in contact with the face or periphery of the shaft e, so that the motion of the large pulley d will 40 impart motion to the pulley f by the belt h. The roller g is kept down in contact with the shaft e by a suitable spring, k, the free end of which bears upon the edge of the plate E. The pulley e has its bearings in a vertically- 45 adjustable box, F, within the frame A, as illustrated in Fig. 4, said box being vertically

adjustable for the purpose of easily tightening or loosening the belt b.

The brush B is arranged diagonally to the saws C and below the same, and an inclined 55 door, G, is hinged to the frame A and covers the upper portion of the brush, whereby the dirt or trash is enabled to slide over and off the door by the assistance of the fan D.

The saws C pass between ribs H, said ribs 60 having extensions l, so that the leaves, stems, and other trash taken from the cotton as it passes through the extensions will pass off onto the door G.

Below the saws C is a mote-board, I, for 65 catching the light trash that would otherwise be carried into the lint-room with the cotton.

The cotton-box K is hinged at m to the frame A, so that it can be raised or thrown back out of the way, when required. The box K has 70 detachably connected to it a cover, L, which forms a top for the frame A, said cover being connected to the box by hooked rods n engaging with eyes or staples p on the cover, whereby said box can be raised at pleasure without the 75 cover being in the way, the latter sliding along over the top of the frame A when the box is raised. The box K has a panel, M, which may be raised or lowered by screws q, upon which the lower edge of the panel rests. The panel 80 M has screws r passing through it horizontally, and these screws have loosely secured to their ends a bar, N, having hooked ends s, to which is detachably connected, at its lower end, a cover, P, which by its own weight keeps 85 closed, but may be readily opened, when required, to insert the cotton. The screws r, as well as the screws q, admit of any degree of adjustability upwardly of the lining or cover P, to better suit the capacity of the saw-chamber to the different sizes of the roll and the various kinds and conditions of seed-cotton to be handled.

Having now fully described my invention, what I claim as new, and desire to secure by 95 Letters Patent, is—

1. The combination, in a cotton-gin, of fan D, pulleys f and g, belt h, shaft e, and saws C, the pulley g being arranged to come in contact with the shaft e, which imparts motion to said 100 pulley g, and to the pulley f, as described.

2. The combination, with the saws C, shaft

- e*, and pulley *d*, of the friction-roller *g*, yielding plate *E*, spring *k*, and the fan *D*, having pulley *f* and belt *h*, substantially as and for the purpose specified.
- 5 3. The combination, with a gin-frame, of the hinged cotton-box *K*, panel *M*, adapted to move up and down to raise and lower said box *K*, cover *P*, bar *N*, with hooked ends *s*, and set-screw *r*, substantially as and for the purpose set forth.
4. The combination, with a gin-frame, of
- the hinged cotton-box *K*, having detachably connected to it the sliding cover *L*, substantially as and for the purpose described.
- In testimony that I claim the above I have 15 hereunto subscribed my name in the presence of two witnesses.

JOHN DU BOIS.
